CLAIM

The ornamental design for a controller bracket, as shown.

DESCRIPTION

FIG. 1 is a perspective view of a controller bracket showing our new design;

FIG. 2 is a top view of the controller bracket shown in FIG. 1;

FIG. 3 is a bottom view of the controller bracket shown in FIG. 1;

FIG. 4 is a side elevational view of the controller bracket shown in FIG. 1. The opposite side elevation is a mirror image of FIG. 4;

FIG. 5 is a front elevational view of the controller bracket shown in FIG. 1; and,

FIG. 6 is a rear elevational view of the controller bracket shown in FIG. 1.
